SEALED FLUID CONTAINER

Chester A. Frick, Glendale, Calif., assignor to
Leo M. Harvey, Los Angeles, Calif.

Application October 9, 1950, Serial No. 189,241

4 Claims. (Cl. 222—209)

1

This invention has to do with a sealed fluid container, and it is a general object of the invention to provide a simple, practical, inexpensive container construction suitable for handling various fluids, particularly liquids, so that the contents of the container are at all times sealed from the surrounding air and yet can be dispensed when desired by simple manipulation of the structure.

There are various fluids, particularly certain liquids, which require or are best handled when excluded from contact with air, and yet are only required occasionally, or in small quantities. The handling or packaging of such materials has heretofore presented a rather difficult problem since ordinary or conventional containers, although capable of handling or carrying a suitable supply of liquid, necessarily allow air to contact material when a portion is dispensed.

It is a general object of this invention to provide a container than can be made in any reasonable or suitable size to handle a supply of liquid, and which can, whenever desired, be operated by mere application of external pressure to dispense or discharge the desired quantities of liquid, ranging anywhere from a minute amount to the entire contents of the container.

It is a general object of the present invention to provide a structure of the general character referred to which is free of complex, costly, or intricate structure and which is such that when the container is empty it can be disposed of without suffering any appreciable economic loss.

It is a further object of the invention to provide a container of the general character referred to which is such that its various parts can be readily formed of materials that are, in most situations, inert, or which can be sterilized, all with the result that the structure is practical for the handling of a wide variety of food products, medical preparations, etc.

The container, as provided by the present invention, involves a body which may be bottle-like in form. The body has a part formed, or may be wholly formed, so that it is flexible and thus subject to being collapsed or flexed by the application of pressure such as may be exerted by the hand of a user. A liquid carrier in the nature of a collapsible or contractible cell is carried within the body and has an outlet duct tubular in form and engaged through the neck of the body. An extension of the outlet duct is folded back over the exterior of the neck of the body, thus establishing the body and carrier in an assembled unit that is easily handled and is suitable

2

for reception of a fluid outlet that will be hereinafter described. An air inlet means is provided in connection with the body, for instance, when the body is bottle-like in form this means may include an air inlet port or passage in the cylindrical side wall of the body, and it is preferred that this port be normally closed as by a removable seal. In practice the seal may be a simple sheet or disc of impervious flexible material applied to the exterior of the body by means of a pressure adhesive.

The fluid outlet used in conjunction with the assembled body and carrier involves a flow handling means and a mounting means applying the flow handling means to the assembled body and carrier. The mounting means may include an annular base applied around the neck of the body to which the outlet duct and its extension have been applied. Assuming the liquid carrier to be formed of a soft rubber, or the like, the extension of the outlet duct folded back over the neck forms an effective seal between the base of the mounting and the neck of the body. A top is carried by the base and fits over the end of the assembled carrier and body. The flow handling means may involve a sleeve which is expandable and a core snugly carried within the sleeve. In a preferred arrangement the sleeve is an integral extension of the unit formed by the base and top and is thus in communication with the interior of the carrier. The core is a rigid unit snugly held in the sleeve, and where the sleeve is round in cross section the core is of like shape. The core has an annular channel in its exterior intermediate its ends dividing it into inner and outer ends, and a port extends from the channel to the outer end of the core. The unit formed by the base, top and sleeve is preferably formed of rubber, or the like, so that when pressure is exerted upon the contents of the carrier the sleeve is expanded away from the inner end of the core with the result that fluid from the carrier passes through the channel and port of the core to discharge from the structure. It is preferred that a sealing cap be initially provided on the outer or terminal end of the sleeve to surround or encase the outer end of the core, the cap being such that it can be readily removed or severed, as by a knife or scissors. In a preferred case a flange projects in from the core to anchor the core to the sleeve and the cap projects from this flange.

Assuming the carrier to have liquid therein and the sealing cap to be severed or opened, and the seal removed from the air inlet of the

body, a user to obtain liquid covers the air inlet as by applying a finger over it, and then applies pressure to the exterior of the body to collapse it to some extent and enough to compress any air between the carrier and body in a manner to force liquid out of the structure in the manner above described.

The various objects and features of my invention will be fully understood from the following detailed description of typical preferred forms of apparatus embodying my invention, throughout which description reference is made to the accompanying drawings, in which:

Fig. 1 is a side elevation of an embodiment of the invention with a dust cap shown thereon and in section. Fig. 2 is a view of the structure with the dust cap removed and showing the structure in use or in the course of being manipulated so that fluid is discharged therefrom. Fig. 3 is an enlarged vertical sectional view of the structure with the dust cap removed, being a view taken in the direction indicated by line 3-3 on Fig. 1. Fig. 4 is an enlarged view of the structure shown in Fig. 2, with certain parts shown in detail to illustrate the operation. Fig. 5 is an enlarged detailed sectional view taken as indicated by line 5-5 on Fig. 3. Fig. 6 is a plan section taken as indicated by line 6-6 on Fig. 5. Figs. 7, 8 and 9 illustrate steps that may be taken in the process of filling the container, Fig. 7 showing the assembled body and carrier, Fig. 8 showing air being introduced to expand the carrier into the body, and Fig. 9 showing liquid being introduced to fill the expanded carrier. Figs. 10 to 13 show an assembled body and carrier with air being exhausted from the body to cause expansion of the carrier into the body. Fig. 11 shows liquid being introduced into the expanded carrier while it is held in the expanded condition. Fig. 12 is a view illustrating the structure shown in Fig. 10 with the neck closed and a seal applied to the air inlet port of the body, following which the neck can be opened leaving the assembled body and carrier to be handled as shown in Fig. 13 where liquid is being introduced into it, and Figs. 14 and 15 illustrate the manipulation of the fluid outlet construction so that air is exhausted from the liquid within the carrier.

The structure as provided by the present invention and as fully shown on sheet 1 of the drawings includes, generally, a body A, a liquid carrier B, air inlet means C for the body and a fluid outlet D carried by or combined with the assembled carrier and body.

The body A may, in practice, vary widely in form and capacity, it being essentially a case-like structure or element with at least a portion thereof flexible so that it can be deflected or pressed inwardly in a manner to create pressure within the body. In the simple form of the invention illustrated in the drawings the body is in the mouth of a case having a neck, and it is essentially bottle-like in form. The particular body shown in the drawings has a cylindrical side wall 10, a bottom 11, a top 12 and a neck 13. In practice it is generally preferred that the body be formed entirely as one integral or continuous unit, in which case a material is employed which affords the desired flexibility to at least a part of the body. In a typical case the entire side wall, bottom and top assembly may be of substantially uniform wall thickness and all such as to be readily flexed by the application of pressure such as can be exerted by the hand of a user, as shown in Fig. 2 of the drawings.

The present invention contemplates formation of the body of various materials or compositions and for purpose of example I will refer to formation of the body entirely of a rubber or rubber-like composition, or of a so-called plastic such as may be suitably molded or otherwise formed into a shape such as I have illustrated in the drawings. An advantage of employing one of the numerous so-called plastics in the formation of the body A is that such materials are reasonably inexpensive, reasonably permanent and strong, and may, if desired, be obtained in transparent or translucent form that may be desirable in connection with certain uses to which the present structure is put.

The carrier B is in the nature of a flexible cell and is such that it can fully occupy the interior of the body A or be reduced in size or collapsed to occur within the body A and be wholly empty. In a typical form of the invention the carrier is formed of rubber, or the like, in which case it is subject to being both expanded and collapsed and may be formed so that it initially tends to occur in the body A substantially as shown in Fig. 7 of the drawings. By employing a carrier of suitable material and of suitable wall thickness, liquid can be filled into it until it completely occupies the interior of the body and it can be contracted or collapsed so that all liquid is extruded from it. It is to be recognized that in practice the composition or material employed in the carrier may be varied, depending upon the material to be handled by the structure. However, in most instances rubber or rubber-like material, either natural rubber, synthetic rubber, or compositions of such materials, when properly selected, answer most purposes.

The carrier in the case illustrated in the drawings has an elongate tubular main portion 20 closed at its lower end by a wall 21 and having an upper end portion 22 in the nature of an outlet duct which fits into and extends through the neck 13 of body A. The outlet duct of the carrier has an extension 23 folded back over the exterior of the neck 13 so that the outlet duct and its extension, in effect, completely encase or surround the neck 13 of the body. It will be apparent that the parts just described can be proportioned so that tight sealing engagement occurs between them and, if desired, suitable sealing agents may be introduced between the engaged parts, or if the material of the body and that of the carrier are both thermo-plastics these parts can be integrally joined together by the application of heat.

The air inlet means C, as provided by the present invention, may, as is shown throughout the drawings, involve merely a simple air inlet port or passage 30 suitably located in the body A. In the case illustrated the body has a limited boss 31 formed on its side wall 10 and the air inlet port 30 is formed in or through the boss. It is preferred that the means C include a seal so that the port 30 can, when desired, be closed, and possibly sealed against the passage of air either into or out of the body. In the preferred form of the invention a seal 35 is applied to the exterior of the body to cover the port 30 and in a typical case the seal 35 may be a sheet of impervious material, preferably a flexible sheet, and it may be held in place as, for instance, over the boss 31, by means of a pressure adhesive.

The fluid outlet D is applied to the assembled body and carrier and serves as a structure for passing fluid out of the carrier. The fluid out-

let involves, generally, a fluid handling means and a mounting for the fluid handling means. The mounting for the fluid handling means in the case illustrated involves a base 40 applied to the neck of the body and a top 41 carried by the base. The base 40 is shown as a tubular element engaged over the neck of the body A to completely surround the neck with the extension 23 of the carrier held between the base and the neck. The top 41, which may be a flat disc-like part carried on or integrally joined with the upper end of the base, preferably seats against the assembled carrier and body so that the extension of the outlet duct 22 engaged around the end of the neck forms a seal between the top 41 and the neck 13. It is to be understood that, if desired, the top or the base, or both, can be welded to or sealed with the parts engaged thereby through sealing mediums, or the parts can be so fitted that a tight engagement is established, making additional sealing agents unnecessary.

The flow handling means preferably involves a sleeve 50 joined to or carried by the top 41 and projecting upwardly therefrom, and a core 51 within the sleeve. In the preferred form of the invention the sleeve 50 is expansible and it is integrally joined with the top 41 which, in turn, is integrally formed with the base 40, making these several parts one integral unit of rubber, or the like. In the particular case illustrated the sleeve 50 is round in cross-sectional configuration, being, in effect, tubular, and the core 51 is of corresponding cross-sectional configuration and is such as to be snugly held in the sleeve. An external annular channel 52 is provided in the core intermediate its ends dividing the core into inner and outer end portions 55 and 56, respectively. A suitable port or system of ports 57 extends from the channel 52 to the extreme upper end 58 of the core. With the construction just described and which is well illustrated in Fig. 3 of the drawings, the lower end of the sleeve is in open communication with the carrier located within the body and when pressure is applied to liquid in the carrier the sleeve 50 expands away from the inner end portion 55 of the core so that the liquid passes out through the port 57 in the manner illustrated in Fig. 4 of the drawings.

It is preferred, in practice, to anchor the core to the sleeve so that these parts remain properly positioned relative to each other and it is desirable to provide the structure with a seal 60. In the case illustrated a flange 61 projects inwardly from the outer end of the sleeve 50 and enters a groove 62 in the exterior of an end extension 63 of the core.

The seal 60 is preferably a closed cap carried by and projecting up from the flange 61. The cap projects above and beyond the terminal end 63 of the core where the port 57 opens. It is preferred that the seal or cap 60 be formed of the same material as, and that it be integral with, the sleeve, top and base, in which case it can be readily removed or opened, as by means of a knife or scissors. When the structure is to be used the closed outer end portion of the cap is simply cut away.

As a convenience in handling and as a guard against possible contamination, it is preferred to provide a cup-shaped dust cap 78 over the upper end portion of the structure in a manner such as is shown in Fig. 1 of the drawings.

With the structure provided by the present 75 exert pressure on the carrier within the body with

invention liquid can be filled into the carrier in various ways. Assuming the body and carrier to be assembled, as shown in Fig. 7 of the drawings, and assuming the carrier to be a unit of rubber, or the like, closed at its lower end and depending into the body from the neck, the carrier can be expanded to take on the size and shape of the interior of the body by introducing air under pressure through the neck, as shown in Fig. 8 of the drawings. In the particular case illustrated a ported cap 71 is applied to the neck 13 and air is introduced through the port 72 of this cap. When the carrier has been expanded into engagement with the inner wall of the body in the course of which expansion air has escaped through the port 30, the seal 35 can be applied, closing port 30 and thus establishing the assembled carrier and body in the condition shown in Fig. 9, so it can be handled as an ordinary bottle and can be filled as, for instance, in the manner illustrated in Fig. 9.

In the case illustrated in Figs. 10 and 11 the carrier is caused to expand into the interior of the body A by withdrawing air from between the body and carrier so that atmospheric air entering the neck expands the carrier into the body. A member 80 is applied over the air port of the body and has a port 81 through which air is exhausted until the carrier is expanded into the body, as shown in Fig. 10. While the member 80 is held in engagement with the body fluid may be filled into the body, as shown in Fig. 11.

If it is desired to handle the assembled carrier and body as a bottle, and without having it engaged by the part 80, a closure 85 can be applied to the neck after air is exhausted through part 80 and the seal 35 applied, following which the part 80 can be removed, as shown in Fig. 12. The structure is then such that it can be used or handled as an ordinary bottle and can be filled, as shown in Fig. 13 of the drawings.

Assuming the assembled body and carrier to be completely filled, that is, filled to the top of the neck, the fluid outlet is applied, as by application of the base 40 over the neck 13 to the position shown in Figs. 14 and 15 of the drawings. As this operation is performed it is desirable that the cap 60 be held compressed or collapsed, as shown in Fig. 14. When the fluid outlet is completely assembled with the combined body and carrier, the cap 60 is released and the resilience of the material of the cap causes it to return to its normal shape, as shown in Fig. 15, with consequent drawing of air through the core so that all air is exhausted from beneath the core. As this operation is performed the seal 35 may be momentarily released or opened, as indicated in Fig. 15, so that atmospheric pressure is exerted on the exterior of the carrier while this operation occurs. With air thus completely exhausted from beneath the core the material in the carrier is held entirely out of contact with air.

From the foregoing description it will be readily understood how the structure can be used and how any desired amount of the liquid from the carrier can be dispensed with a minimum of effort and without any resort to complicated manipulation or equipment. Assuming the cap 60 to be opened as by means of a knife or scissors the container can be arranged or disposed as shown in Fig. 2, while it is held in the user's hand. The user can place a finger or his thumb over the port 30 in the body and then squeeze the body in a manner to collapse it somewhat. This will

consequent discharge of liquid past the core and from the port 57. As soon as the pressure is released from the body the sleeve collapses back into the core and when the finger is removed from the port 30 air fills in between the carrier and the interior of the body making the structure ready for another operation. If the structure is thus operated a quantity of liquid that has been held out of contact with air is dispensed from the device and this will continue to be true until all of the liquid has been displaced from the carrier.

Having described only typical preferred forms of my invention, I do not wish to be limited or restricted to the specific details herein set forth, but wish to reserve to myself any variations or modifications that may appear to those skilled in the art and fall within the scope of the following claims.

Having described my invention, I claim:

1. A container including, a body with a flexible portion and having a neck, a flexible liquid carrier in the body and having an outlet duct sealed with the neck, and a device carried by the neck and passing liquid from the duct, the said device being normally closed against the passage of liquid and being opened to pass liquid by pressure on liquid in the carrier, said device having a mounting applied to the neck and having a sleeve and a core snug in the sleeve, the sleeve being expandable and the core being ported to pass liquid when the sleeve is expanded.

2. A container including, a body with a flexible portion and having a neck, a flexible liquid carrier in the body and having an outlet duct sealed with the neck, and a device carried by the neck and passing liquid from the duct, the said device being normally closed against the passage of liquid and being opened to pass liquid by pressure on liquid in the carrier, said device having a mounting applied to the neck, a sleeve, a ported core snug in the sleeve, the sleeve normally covering the port of the core and being expandable to pass fluid from the carrier, and means for withdrawing air from between the core and the liquid in the carrier.

3. A container including, a body with a flexible portion and having a neck, a flexible liquid carrier in the body and having an outlet duct sealed

with the neck, and a device carried by the neck and passing liquid from the duct, the said device being normally closed against the passage of liquid and being opened to pass liquid by pressure on liquid in the carrier, said device having a mounting applied to the neck, an expandable sleeve carried by and projecting from the mounting and in communication with the carrier, a ported core in the sleeve and normally snugly embraced thereby, and a collapsible sealing cap checking access to the core.

4. A container including, a body with a flexible portion and having a neck, a flexible liquid carrier in the body and having an outlet duct sealed with the neck, and a device carried by the neck and passing liquid from the duct, the said device being normally closed against the passage of liquid and being opened to pass liquid by pressure on liquid in the carrier, said device having a mounting applied to the neck, an expandable sleeve carried by and projecting from the mounting and in communication with the carrier, a ported core in the sleeve and normally snugly embraced thereby, and a collapsible sealing cap checking access to the core, the mounting, sleeve and cap being formed as a unit of rubber-like material.
